FIG. I

FIG.2

FIG. 3

10 12 INVENTION
Albert W. Calvins
by R.D. Little
his Attorney

UNITED STATES PATENT OFFICE.

ALBERT W. CALVIN, OF PITTSBURGH, PENNSYLVANIA.

ANTIFRICTION SIDE BEARING.

1,320,122.

Specification of Letters Patent.

Patented Oct. 28, 1919.

Application filed July 10, 1918. Serial No. 244,245.

To all whom it may concern:

Be it known that I, ALBERT W. CALVIN, a citizen of the United States, and a resident of Pittsburgh, in the county of Allegheny and State of Pennsylvania, have invented certain new and useful Improvements in Antifriction Side Bearings, of which the following is a specification.

My invention relates to anti-friction side 10 bearings for cars used on steam, electric, or other railways.

One object of the invention is to provide a side bearing in which provision is made for the full angular movement of the car 15 bolsters with a differential lateral movement of the anti-friction member of the side bearing.

Another object of the invention is to provide a side bearing in which the bearing surfaces are straight from end to end and wherein the formation of the relatively 20 movable members of the bearing from high grade rolled or forged steel and from steel of stock sizes is made possible.

Another object of the invention is to provide an anti-friction side bearing for railway cars having a balanced roller with a gravity return roller adapted to engage with and automatically maintain the balanced 25 roller in a substantially central position on the lower bearing plate of the side bearing.

A further object of my invention is to provide a side bearing having novel features of construction whereby the bearing is made 30 applicable for use on both truck or body bolsters.

A still further object of my invention is the provision of an anti-friction side bearing having the novel constructions, combinations 35 and arrangement of parts shown in the drawings, to be described in detail herein-after, and to be particularly specified in the appended claims.

Referring now to the drawings, forming 40 part of this specification, Figure 1 is an end elevation, partly in section of my improved bearing, the section being taken on the line I—I of Fig. 2.

Fig. 2 is a side elevation of the same, 45 partly in section, the section being taken on the line II—II of Fig. 1.

Fig. 3 is a side elevation, partly broken away, showing a modified form of side bearing, in which the bearing cage is secured to 50 the truck bolster, instead of as in Figs. 1 and 2, to the body bolster of a railway car.

Fig. 4 is a sectional end elevation, showing part of the apparatus of Fig. 3, the section being taken on the line IV—IV of Fig. 3.

In the accompanying drawings a side bearing embodying my invention is shown operatively mounted between opposite end portions 2 and 3 of the truck and body bolsters of a railway car. The bearing has a bottom bearing plate 4 on the truck bolster 65 2 and a top bearing plate 5 on the body bolster 3 with an interposed anti-friction roller 6 between the plates 4 and 5. The roller 6, which is annular in cross section, is loosely mounted within the housing or cage 7 of the 70 bearing, and is arranged to roll on the contiguous flat, plane surfaces of the bearing plates 4 and 5. Being circular in cross section, the roller 6 is balanced and will not roll or move, until acted upon by some out- 75 side force.

As shown in Figs. 1 and 2, the cage 7, which has vertical side walls 8, 8 and end walls 9, 9 is fastened to the body bolster 3 by means of the integral flanges 10, 10 on 80 opposite sides of the cage, and the top bearing plate 5 on the interior of the cage is secured to the upper side wall 11 of the cage 7. The lower side 12 of this cage 7 is open and has no wall and the roller 6 projects 85 downwardly through the open side of the cage into engagement with the bearing surface of the bottom bearing plate 4, which is fastened directly to the truck bolster.

Extending through each side wall 8 of 90 the cage of Figs. 1 and 2 is an opening or slot 13 with the lower edge 14 of the slot 95 inclined from both ends toward the middle of its length, the proclivous edges 14 intersecting a short intermediate section 14, which is horizontal. The slots 13 in the opposite side walls 8, 8 are in horizontal alignment and extending through these slots and through the opening 15 in the hollow roller 6 is a cylindrical gravity return roller 100 or pin 16, this pin having a head 17 on one end and a removable collar 18 on the other, which form abutments on the exterior of the cage 7 and add weight to the gravity roller pin 16. The collar 18 is detachably secured 105 on the roller 16 by means of a cotter pin 19, which extends through a transverse hole in the end of the gravity roller.

By reference to Figs. 1 and 2, it will be seen that the gravity roller 16 engages with 110 the cylindrical surface of the hole 15 in the annular roller 6 and with the lower edge 14

of the slots 13 so that when relative swiveling movement of the bolsters 2 and 3 occurs and the balanced roller 6 is moved thereby, the gravity return roller 16 is caused to ride 5 upward on the inclined edges 14 of the slots 13. It also will be readily seen that when the bolster 3 lifts clear of the roller 6, that the gravity return roller 12 will roll down the inclined edges 14 of the slots 13 by gravity, and will automatically engage with and 10 return the bearing roller 6 into its central position, (that shown in full lines in Figs. 1 and 2 of the drawings).

It will be obvious that by reversing the 15 angle of inclination of the slots 13 in the side walls 8 of the cage of Figs. 1 and 2, that the cage can be fastened to the truck bolster instead of to the body bolster 3, as shown, and the bearing thereby made applicable for use 20 as a truck bearing instead of a body bearing.

In the modified construction of Figs. 3 and 4, the bearing is operatively mounted between end portions 2 and 3 of the truck bolster and body bolster and has a bottom 25 bearing plate 4 and top bearing plate 5 with an annular, balanced roller 6 between the contiguous wearing surfaces of the plates 4 and 5.

When the travel or relative swiveling 30 movement of the bolsters 2 and 3 is great enough, the roller 6 preferably will be in the form of a hollow truncated cone and the included angle between the wearing faces of the bearing plates 4 and 5 will be the same 35 as that of such tapering, anti-friction roller, as shown in Figs. 3 and 4.

The cage 7 of this bearing is secured by the flanges 10, 10 on the sides thereof to the truck bolster 2, instead of (as in Figs. 1 and 40 2) to the body bolster 3, and the bottom bearing plate 4 is fastened, on the interior of the cage, to the wall forming the lower side 12 of this cage. The upper side 11 of this cage has no wall, the roller 6 projecting 45 upwardly above the cage, in position to be operatively engaged by the wearing surface of the top bearing plate 5.

Obviously both the upper side 11 and the lower side 12 of the cages in either form of 50 side bearing may be made open instead of only one as shown, in such case both bearing plates 4 and 5 being fastened directly to the bolsters 2 and 3.

Instead of having proclivous slots 13 extending through the side walls 8, 8 of the bearing (like those shown in Figs. 1 and 2), the side walls 8, 8 of the bearing of Figs. 3 and 4 have recessed slots 13 which extend outwardly from the inner surfaces of the 60 vertical side walls 8. (See Fig. 4). The lower edges 14 of the recessed 13 are inclined from the outer ends toward the middle of the length thereof and intersect with a horizontal section 14^a thereof, in the same 65 manner as in Figs. 1 and 2. A cylindrical

gravity roller or pin 16 extends through the hollow roller 6 of Figs. 3 and 4 and its ends extend loosely into the opposite recessed slots 13 in the side walls 8, 8. A hole 20 in one side wall 8 provides means for the insertion of the pin 16 within the cage and roller in assembling the parts, this hole being located at some distance above the axis of the pin 16 when in central position on the wearing surface of the bearing plate 4. (See 75 Fig. 3). On account of having a closed lower side or bottom 12 the end walls 9, 9 are provided with openings 21, and the side walls 8, 8 with openings 22, which permit dirt, snow, ice and similar foreign materials 80 from accumulating within the cage 7 and on the wearing surface of the bearing plate 4.

The operation of the side bearing, which will be readily understood, will now be described.

When the bolsters 2 and 3 are cleared and the roller 6 is free to roll, as is the case normally, the gravity roller 16 rolls on the edges 14, of the proclivous slots 13 to the lowest point 14^a of the edges of the slots, 90 which, as shown in the drawings is at the middle of the length of the slots. When the body bolster 3 moves downwardly into engagement with the roller 6 and the truck swivels under the car, the roller 6 travels 95 on the bottom bearing plate 4 toward the one end or the other of the bearing plates (toward or into the position shown dotted in Figs. 2 and 4) and affords a bearing for the body bolster which is substantially without friction.

In traveling toward the end of the bearing plate 4, the roller 6 engages the gravity roller or pin 16 and moves it toward one end of the slots 13 in the side walls of the cage 7, 105 the inclined lower edge 14 of the slots causing the gravity pin 16 to lift or roll upwardly, this movement of the pin also being effected without any substantial amount of friction.

As soon as the body bolster 3 lifts and the roller 6 is thereby freed the pin rolls 110 backwardly down the inclined lower edges 14 of the slots 13 and by engagement with the balanced, anti-friction roller 6, moves it back until in substantially its central position. In this way the roller 6 is always automatically moved back into central position whenever the car rights itself and provides the usual clearance in the side bearings and the roller 6 remains in its central position to again receive the load of the body bolster and to roll either to the right or the left, depending upon the direction of swiveling movement of the truck and truck bolster 2. By making the edges 14^a horizontal at the middle of the length of the slots 13 it will be unnecessary for the roller 6 to always return to the mathematical center of the bearing plate, which results in the wear 120 125 130

on the bottom bearing plate being distributed over some distance on the length of the plate and the life of the bearing plate being materially increased. The rollers 6 and 16 5 being loosely mounted in the cage with only a frictional engagement between them, the considerable amount of jolting to which railway cars are subjected will cause the roller 6 to turn slightly from time to time and in this way present different portions of 10 its periphery to the bearing plate, so that wear in spots on the roller and bearing plates is avoided and overcome.

With side bearings embodying the novel features of my invention as shown the balanced roller has a rolling contact with the wearing faces of the bearing plates and having a differential movement, the travel or 15 bodily movement is very short compared to the swiveling movement of the truck and body bolsters of the car. The balanced roller of Figs. 3 and 4 may be cylindrical instead of a truncated cone as shown and the gravity roller or pin also may be cylindrical when found necessary or desirable.

My improved side bearing is of simple construction, is strong and durable and is easily and cheaply constructed and the wearing parts are readily made from stock sizes 20 of merchant steel.

The bearing roller is secured to the cage in a simple manner which enables the roller to turn freely and present different surfaces to contact with the bearing plates and the 25 friction is reduced to a minimum.

Many modifications, which will suggest themselves to those skilled in the art, may be made in the detailed construction of the side bearings within the scope of the 30 appended claims.

What I claim is:

1. An anti-friction side bearing comprising upper and lower bearing plates, an interposed circular roller, vertical walls associated with one of said bearing plates and provided with guides inclined from both 45 ends toward the center thereof, and a gravity returning member loosely engaging said roller and said guides and arranged to return said roller to near the central position.

2. An anti-friction side bearing comprising upper and lower bearing plates, an interposed circular roller, side walls associated with one of said bearing plates and provided with guides inclined from both ends toward the center thereof, and a weighted 55 centering member operatively engaging said guides and loosely engaging said roller.

3. An anti-friction side bearing comprising upper and lower bearing plates, an interposed annular roller, forming a hollow anti-friction member, side walls associated with one of said bearing plates and provided with grooves inclined from both ends 60 to the center, and a gravity return roller

operatively engaging said guides and extending through said hollow roller.

4. An anti-friction side bearing comprising upper and lower bearing plates, an interposed annular roller forming a hollow 70 circular anti-friction member, side walls associated with one of said bearing plates and provided with grooves inclined from both ends toward the center, and a weighted guide pin projecting through the roller and 75 through said grooves and provided with abutments at both ends outside of said side walls.

5. An anti-friction side bearing comprising upper and lower bearing plates, an interposed annular roller forming a hollow 80 circular anti-friction member, side walls associated with one of said bearing plates and provided with guides inclined from both ends to the center, and a circular roller returning member in rolling engagement with said guides and loosely engaging said roller from the inside.

6. An anti-friction side bearing comprising upper and lower bearing plates, an interposed hollow circular roller forming an annular anti-friction member, a cage having side walls associated with one of said bearing plates and provided with guide slots inclined from both ends toward the 95 center, and a circular pin extending through said hollow roller and through said slots and in rolling engagement with said slots and provided at its ends exteriorly of the side walls with enlargements.

7. An anti-friction side bearing comprising upper and lower bearing plates, an interposed balanced roller adapted to operatively engage with said bearing plates, a gravity return roller adapted to engage with 105 and automatically maintain the balanced roller into its central position and a cage in which said rollers are operatively mounted.

8. An anti-friction side bearing comprising upper and lower bearing plates, an annular balanced roller between said bearing plates, a gravity return roller extending through the annular roller, a cage in which said rollers are operatively mounted and means on the side walls of the cage engaging with the gravity return roller and co-acting therewith to maintain the annular roller in its central position.

9. An anti-friction side bearing comprising upper and lower bearing plates, a balanced roller between said bearing plates, a gravity return roller, a cage in which said rollers are operatively mounted and praeclivous recesses or slots in the side walls of the cage, said return roller extending into 120 the recesses or slots and co-acting therewith to automatically return the balanced roller into its central position.

10. In an anti-friction side bearing, the combination with upper and lower bearing 130

4
plates, of an interposed circular roller, vertical walls associated with the lower bearing plate and provided with guides inclined from both ends to the center, and a roller returning member loosely engaging said roller and said guides and arranged by gravity to return said roller to near the central position.

11. In an anti-friction side bearing, the combination with upper and lower bearing plates, of an interposed circular roller, side walls associated with the lower bearing plate and provided with guides inclined from both ends to the center, and a weight-ed centering member operatively engaging said guides and loosely engaging said roller.

12. In an anti-friction side bearing, the combination with upper and lower bearing plates, of an interposed hollow circular roller or annular anti-friction member, side

walls associated with the lower bearing plate and provided with guides inclined from both ends to the center, and a circular roller-returning member in rolling engagement with said guides and loosely engaging said roller from the inside. 25

13. In an anti-friction side bearing, the combination of a housing arranged for attachment to the truck bolster and provided with a bearing surface and openings at the level of said surface, a circular roller, the side walls of said housing being provided with guides inclined from both ends to the center, and a roller-returning member loosely engaging said roller and said guides 35 and arranged by gravity to return said roller to near the central position.

In testimony whereof I have hereunto set my hand.

ALBERT W. CALVIN.
